REFLECTING GARMENT FOR TRAFFIC DIRECTORS

Joseph De Grazia, Washington, D. C.

Application February 12, 1953, Serial No. 23,686

Term of patent 14 years

(Cl. D3—4)

(Granted under Title 35, U. S. Code (1952),
sec. 266)

To all whom it may concern:

The invention described herein may be manufactured and used by or for the Government for governmental purposes, without the payment to me of any royalty thereon.

Be it known that I, Joseph De Grazia, a citizen of the United States and resident of the city of Washington, in the District of Columbia, have invented a new, original, and ornamental Design for a Reflecting Garment for Traffic Directors, of which the following is a specification, reference being had to the accompanying drawings, forming a part thereof.

Figure 1 is a front elevational view of a reflecting garment for traffic directors showing my new design;

Figure 2 is a rear elevational view thereof; and

Figure 3 is a perspective view of the same.

The essential features of the invention are shown in full lines.

I claim:

The ornamental design for a reflecting garment for traffic directors, substantially as shown and described.

JOSEPH DE GRAZIA.
